UNITED STATES PATENT OFFICE.

PHILIP PISTOR, OF PHILADELPHIA, PENNSYLVANIA, ASSIGNOR TO THE SOUTHWARK FOUNDRY AND MACHINE COMPANY, OF SAME PLACE.

DUPLEX STEAM PUMPING-ENGINE.

SPECIFICATION forming part of Letters Patent No. 309,797, dated December 23, 1884.

Application filed August 18, 1884. (No model.)

To all whom it may concern:

Be it known that I, PHILIP PISTOR, a citizen of the United States, and a resident of Philadelphia, Pennsylvania, have invented certain Improvements in Duplex Steam-Pumping Engines, of which the following is a specification.

My invention relates to duplex pumps of that class of which the Worthington pump is an example, and in which the steam-valve of one pump derives its movement from the piston-rod of the other pump.

The object of my improvement is to provide such a pump with means whereby either pump can be run separately where it is not desired to run both pumps, and this object I attain in the manner hereinafter set forth, reference being had to the accompanying drawings, in which—

20 Figure 1 is a perspective diagram of sufficient of a duplex pumping-engine to illustrate my invention; and Figs. 2 and 3 transverse sections, partly in elevation, of parts of the mechanism.

25 A and A' are the piston or plunger rods of the two pumps, the cylinders and barrels of which are arranged side by side, as usual; and B B' are the valve-rods of the two engines.

30 The rod A has a socket or cross-head, a, which is connected by a rod, b, to a rocker, D, on a shaft, F; and the rod A' has a similar socket or cross-head, a', connected by a rod, b', to a rocker, D', on a shaft, F'. The valve-rod B is connected by a rod, d, to an arm, f, 35 on one end of a rock-shaft, G, the other end of which has a bell-crank lever, H, and the long arm of the latter has a pin, g, to which is adapted the hooked upper end of a rod, I, the lower end of which is connected to an arm, h', on the rocker-shaft, F'. The valve-rod B' 40 is similarly connected by a rod, d', to an arm, f', on a rock-shaft, G', the bell-crank lever H' of which has a pin, g', for the reception of the hooked upper end of a rod, I', the lower end 45 of which is connected to an arm, h, on the rocker-shaft F. The lever H' is broken away in Fig. 1, in order to show the upper end of the rod I', but the two levers, H H', and their pins g g' are shown in proper relation to each 50 other in Fig. 3. This is the ordinary arrange-

ment in common use, whereby the piston-rod of one engine is caused to actuate the valve-rod of the other engine, the two engines being thus dependent one upon the other, so that neither can be run separately.

55 In carrying out my invention I mount upon any available part of the engine-framing a steam-cylinder, J, the piston-rod *j* of which has a connecting-rod, K, hooked at the outer end for adaptation to a pin, *m*, the latter having a tapered shank, *m'*, which can be fitted to an opening in the short arm of either of the bell-crank levers H H', and secured in position by a nut, *m* ², Fig. 3. The valve-stem *k* of the cylinder J has a pair of transverse 60 plates, *p*, forming a socket for the reception of the short arms of a pair of bell-crank levers, M M', secured to a rod, *s*, carried by brackets *s'* on the cylinder. Arms N N' are loosely hung to the rod *s*, and the arm N can be coupled 65 to the lever M, or the other arm, N', to the lever M' by inserting a pin through an opening, *w*, in the arm, and a similar opening in the arm *t* of the lever. The arm N is connected 70 by a rod, *x*, to an arm, *y*, on the rocker-shaft 75 F, and the arm N' by a similar rod, *x'*, to an arm, *y'*, on the rocker-shaft F'. By the above arrangement either engine can be worked independently of the other, on first throwing the rods I I' out of gear with the bell-crank levers 80 H H'. For instance, when it is desired to work the engine of which A is the piston-rod, the arm N is locked to the arm *t* of the lever M, (the arm N' being disconnected from the lever M'), and the valve-stem *k* of the cylinder J is thus 85 brought under control of the rocker-shaft F. The pin *m* being secured to the short arm of the lever H, the hooked end of the connecting-rod K is adapted thereto, and the main valve-rod B is thus brought under control of the piston-rod *j*, so that the operation of the valve is 90 controlled by its own engine. If the other engine is to be operated, the pin *m* is shifted to the lever H', the arm N is released from the lever M, and the arm N' coupled to the lever M'. 95

To regulate the movement of the piston in the cylinder J, I use a governing-cylinder, P, having a valved passage between the opposite ends, as usual, and filled with oil or other 100

liquid, a piston in this cylinder having a rod, *j*', connected to the rear projecting end of the piston-rod *j*.

Although I have shown special means for operating the valve-stem *k* from either rocker-shaft *F F'*, and a special means of connecting the rod *K* to either of the shafts *G G'*, my invention is not limited thereto, as those details may be modified in various ways without departing from the spirit of my invention.

I claim as my invention—

1. The combination of the rocker-shafts *F F'* of a duplex pump, the valve-operating rock-shafts *G G'*, the cylinder *J*, with its piston-rod and valve-stem, and devices, substantially as described, whereby said valve-stem is operated from either of the shafts *F F'*, and the piston-rod is connected to either of the shafts *G G'*, as set forth.

2. The combination of the shafts *G G'* and their levers *H H'* with the cylinder *J*, its piston-rod *j* and rod *K*, and the pin *m*, having a stem adapted to openings in either of the levers, as set forth.

3. The combination of the cylinder *J* and its valve-stem, the levers *M M'*, the arms *N N'*, the rocker-shafts *F F'*, and means for connecting the arms to the rocker-shafts, and for locking said arms to or releasing them from the levers, as set forth.

In testimony whereof I have signed my name to this specification in the presence of two subscribing witnesses.

PHILIP PISTOR.
